UNITED STATES PATENT OFFICE.

CHARLES A. LUNDY, OF RENO, NEVADA.

GAS-ENGINE.

1,092,113.

Specification of Letters Patent. Patented Mar. 31, 1914.

Application filed December 9, 1912. Serial No. 735,590.

To all whom it may concern:

Be it known that I, CHARLES A. LUNDY, a citizen of the United States, residing at Reno, in the county of Washoe and State 5 of Nevada, have invented certain new and useful Improvements in Gas-Engines, of which the following is a specification.

My invention relates to the class of gas engines.

10 My invention is especially adapted for water-cooled engines, and it has for its objects to dispense with the use of puppet valves and to provide a simple, effective and durable construction and arrangement by 15 which the explosive mixture is admitted to the cylinder, is exploded therein, and the products of explosive combustion are exhausted therefrom in timely succession.

To these ends my invention consists in 20 the novel gas engine which I shall now fully describe by reference to the accompanying drawings in which—

Figure 1 is a vertical section of my gas engine. Fig. 2 is a plan of the same.

25 1 is the crank case which is here shown as constituting the bed of the engine.

2 is the cylinder secured to the bed by bolts 3. The cylinder is here shown as provided with a water-jacket 4, for the reason 30 that my invention as herein disclosed is applicable to water-cooled engines, because the cylinder is non-rotatable and, therefore, permits the necessary connections to be made.

35 5 is the piston; 6 is the connecting rod; 7 is the crank of the crank-shaft 8, and 9 is the fly wheel, all arranged according to accepted practice.

In the head 10 of the cylinder are made 40 two ports. One of these 11 is the intake port, and the other 12, indicated in Fig. 1 by dotted lines and by the dotted arrow, is the exhaust port. These ports as is shown in Fig. 2 lie in the arc of a circle, in order 45 that they may successively be registered with the port of the rotating valve-plate. This valve plate is 13, and its single port is 14, as shown in Fig. 1.

15 15 is a cap screwed upon the top of the 50 cylinder 2. This cap is provided with an intake connection opening 16 which is vertically aligned with the intake port 11 of the cylinder. The cap is also provided with an exhaust connection opening 17 which is 55 vertically aligned with the exhaust port 12 of the cylinder.

The valve plate 13 is centrally pivoted and is rotated by the following connections. 18 is a shaft which carries the valve plate 13. This shaft is journaled in the 60 cap 15 in a suitable stuffing box 19, and it has on its upper end a gear 20. 21 is a short countershaft mounted in bearings 22 of the cap 15. One end of the countershaft carries a pinion 23 which meshes with the 65 gear 20 on the shaft 18. Its other end carries a bevel gear 24 which meshes with a bevel gear 25 on the upper end of a vertical shaft 26 mounted above in a bearing 27 on the cap 15 and below in a bearing 28 in 70 the crank case 1. The lower end of the shaft 26 carries a gear 29 which meshes with a gear 30 on the crank-shaft 8 of the engine.

Ball-bearings 31 are located between the 75 upper surface of the valve-plate 13 and the under surface of the cap 15. In order to make a proper joint or bearing between the under surface of the valve plate 13 and the cylinder, I interpose between said 80 plate and the cylinder top a smooth surfaced bearing plate 32 upon which the valve plate bears, and said bearing plate is provided with two sleeves 33, one of which extends down into the intake port 11 of the 85 cylinder head, and the other into the exhaust port 12 thereof, said sleeves having packing rings 34. It will be seen by reference to Fig. 1 that the carrying shaft 18 of the valve plate 13 projects down through 90 the bearing plate 32 and has fitted around its lower end a spring 35, the function of which is to hold the bearing plate up to the valve plate with yielding pressure sufficient to make a close joint, the proper lubrication of which is provided for by oil supplied to the space or chamber 36 left between the bearing plate and the cylinder top. This oil space or chamber is formed by reason of the fact that the walls of the 100 cylinder-ports 11 and 12 rise above the cylinder top, as shown in Fig. 1, and the bearing plate lies above the tops of said walls.

37 is the spark plug.

It is to be understood that the gearing of 105 the transmitting connections between the crank shaft 8 and the valve plate 13 will be proportioned to effect the timely rotation of said valve-plate, in order that its single port 14 will successively and in proper time 110 register with and open and close the intake and exhaust connections and ports.

By the constructions shown it will be seen that the valve plate is well seated, is subject to a minimum of wear, and can be readily reached when necessary. Being well lubricated, its action is practically noiseless, and it will require but little attention.

Though I have herein shown but one cylinder, it is to be understood that a plurality of cylinders may be used.

10. I claim:—

1. In a gas engine, the combination of a cylinder having separate ports in its head for the admission of the explosive mixture and the exhaust of the products of explosive combustion, said ports having their walls extended above the upper surface of the cylinder head; a cap secured upon the cylinder and having an intake-connection opening alined with the admission port of the cylinder and a separate exhaust-connection opening alined with the exhaust port of the cylinder; a rotatable valve-plate lying between the cylinder and its cap and having a single port adapted by the rotation of the plate to register successively with the alined connection openings of the cap and the ports of the cylinder head; a bearing plate having downwardly projecting sleeves packed in the ports of the cylinder head, said plate lying in contact with the valve-plate and separated from the upper surface of the cylinder head to leave an intervening oil space; means for exploding the mixture in the cylinder; and means driven by the engine for effecting the timely rotation of the valve-plate.
2. In a gas engine, the combination of a cylinder having separate ports in its head for the admission of the explosive mixture and the exhaust of the products of explosive combustion, said ports having their walls extended above the upper surface of the cylinder head; a cap secured upon the cylinder and having an intake-connection opening alined with the admission port of the cylinder and a separate exhaust-connection opening alined with the exhaust port of the cylinder; a rotatable valve plate lying between the cylinder and its cap and having a single port adapted by the rotation of the plate to register successively with the alined connection openings of the cap and the ports of the cylinder head; a bearing plate having downwardly projecting sleeves packed in the ports of the cylinder head, said plate lying in contact with the valve-plate and separated from the upper surface of the cylinder head to leave an intervening oil space; means for exploding the mixture in the cylinder; and means driven by the engine for effecting the timely rotation of the valve-plate.

tion openings of the cap and the ports of the cylinder head; a bearing plate having downwardly projecting sleeves packed in the ports of the cylinder head, said plate being separated from the upper surface of the cylinder head to leave an intervening oil space; means for holding said bearing plate up into contact with the valve plate; a shaft carrying said valve plate, said shaft extending upwardly through the cap and downwardly into the oil space; and power transmitting connections from the engine to said shaft for driving it to effect the timely rotation of said valve plate.

3. In a gas engine, the combination of a cylinder having separate ports in its head for the admission of the explosive mixture and the exhaust of the products of explosive combustion; a cap secured upon the cylinder and having an intake-connection opening alined with the admission port of the cylinder and a separate exhaust-connection opening alined with the exhaust port of the cylinder; a rotatable valve-plate lying between the cylinder and its cap and having a single port adapted by the rotation of the plate to register successively with the alined connection openings of the cap and the ports of the cylinder head; a bearing plate fitted with packed sleeves in the ports of the cylinder head; a pivot shaft mounted in the cap and carrying the valve-plate, said shaft passing down through the bearing plate; a spring around the lower end of the pivot shaft arranged to press and hold the bearing plate in contact with the valve plate; means for exploding the mixture in the cylinder; and means for effecting the timely rotation of the valve-plate comprising the engine piston, the crank-shaft driven thereby, and power transmitting connections between said crank-shaft and the pivot-shaft which carries the valve-plate.

In testimony whereof I have signed my name to this specification in the presence of two subscribing witnesses.

CHARLES A. LUNDY.
